UNITED STATES PATENT OFFICE.

WALTER J. SMITH, OF PHILADELPHIA, PENNSYLVANIA.

WOOD-MOLDING MACHINE.

SPECIFICATION forming part of Letters Patent No. 376,269, dated January 10, 1888.

Application filed May 4, 1887. Serial No. 237,087. (No model.)

To all whom it may concern:

Be it known that I, WALTER J. SMITH, of Philadelphia, in the county of Philadelphia and State of Pennsylvania, have invented a new and useful Improvement in Wood-Molding Machines, of which the following is a full, clear, and exact description, reference being had to the accompanying drawings, and to the letters of reference marked thereon.

10 My invention consists of an appliance which can be adjustably attached to a wood-molding machine, such as shown and described in my pending application, Serial No. 236,753, filed May 2, 1887, and by means of which I am enabled to describe a segment of a circle of any radius without being obliged to find the center of such circle, and my improved appliance can be further used as a bearing for molding curved work.

15 In the drawings, Figure 1 is a front view of a wood-molding machine with my appliance attached. Fig. 2 is a perspective view of my appliance detached; and Fig. 3, a detail top view, partly in cross-section, showing the manner of attaching the angle-irons.

Similar letters of reference indicate similar parts in all the figures.

A is a plate attached to the front of the frame of a wood-molding machine having the 30 T-shaped grooves *a* formed therein.

B B' are angle-irons provided with slotted segmental projections *b b'* and with projections *c c'*, having slots parallel with the angle-irons. The angle-irons are beveled at their upper 35 ends, so that they can be adjusted at an angle of forty-five degrees. The angle-irons are attached to the frame A by means of T-headed bolts *h*, inserted in the T-shaped grooves *a* and passing through the slots in the angle-irons. It will be seen that the angle-irons can be adjusted on the plate A at any desired angle 40 of not less than forty-five degrees, the point of contact of the angle-irons being in a line with the axis of the tool-spindle C.

45 For forming the segment of a circle of any radius without finding the center the operation is as follows: Supposing it is required to form a segment of a circle having a spring of

thirty inches to a base of eight feet, I take a piece of board, as D, (shown in dotted outline 50 in Fig. 1,) and draw a line, *d d*, eight feet in length. From a point midway of this line I draw a line, *e e'*, at a right angle to the line *d d*, thirty inches in length. Supposing the distance from the cutting-tool to the apex of the 55 angle-bars is four inches, I take two nails and drive them into the board on the line *d d* at points four inches from each end of the line *d d*, as shown at *g g*. The angle-bars are then adjusted so that when the board is supported by 60 the nails *g g* in a true horizontal plane on the angle-bars and the cutting-tool is in contact with the board at the point *e'* they will be in the requisite position, and by starting the cut at one end of the line marked *d d* on the board 65 and advancing the board, constantly keeping the nails bearing on the angle-irons, a cut will be made in a true circle from end to end of the line, and thus form a segment of a circle 70 having the requisite spring and base length.

Having described my invention, I claim—

1. In a wood-molding machine, the combination, with a cutting-tool and a front plate provided with a series of parallel grooves, of a pair of angle-irons or supports having plane 75 bearing-surfaces arranged at an angle to the axis of the cutting-tool, and headed bolts adjustable in the parallel grooves, whereby said angle-irons are secured, substantially as specified.

2. In a wood-molding machine, a cutting-tool and a front plate having a series of parallel grooves, combined with a pair of angle-irons or supports having plane bearing-surfaces arranged at an angle to the axis of the 85 cutting-tool, said angle-irons being provided with elongated slots, and supports adjustably retained in said slots and in the parallel grooves, substantially as specified.

In testimony whereof I have hereunto set 90 my hand and seal.

WALTER J. SMITH. [L. S.]
